UNITED STATES PATENT OFFICE.

EDWARD H. ERNST, OF WASECA, MINNESOTA.

JOURNAL-LUBRICATOR.

1,222,857.

Specification of Letters Patent. Patented Apr. 17, 1917.

Application filed September 25, 1916. Serial No. 122,097.

To all whom it may concern:

Be it known that I, EDWARD H. ERNST, a citizen of the United States, residing at Waseca, in the county of Waseca and State 5 of Minnesota, have invented certain new and useful Improvements in Journal-Lubricators, of which the following is a specification.

This invention relates to an improved journal lubricator and the principal object 10 of the invention is to provide a journal lubricator which can be used in connection with railway cars or other vehicles and which is so constructed that the axle and hub of the wheel will be lubricated, a lubricant pocket being provided and the lubricant being applied to the axle and wheel hub by means of wicks or wipers carried in the receptacle and extending to engage the axle and wheel hub.

20 Another object of the invention is to so construct this journal lubricator that the lubricant receptacle will be supported beneath the axle and to further so mount this receptacle that it may be lowered when it is 25 desired to refill the receptacle or replace the wicks.

This invention is illustrated in the accompanying drawings, wherein:—

Figure 1 is a view showing the journal 30 box and lubricator in elevation with the axle shown in section.

Fig. 2 is a vertical transverse sectional view through the lubricator and axle, taken on the line 2—2 of Fig. 3.

35 Fig. 3 is a vertical longitudinal sectional view through the lubricant receptacle with the axle and a portion of the wheel hub indicated by dotted lines.

The axle 10 which will be provided at 40 each end with a wheel 11 will be mounted in the car truck in the usual manner and will extend through the journal boxes of the car truck. The journal box shown in Fig. 1 includes the upper and lower bars 12 and 13 which may form a part of the car truck and the vertical or side bars 14 which are secured to the upper and lower bars by means of bolts 15. These side bars 14 carry eyes 16 and are positioned adjacent the lower bars 13. The

50 Babbitt faced brass 17 engages the upper portion of the axle 10, and is suspended from the carrier 18. The yokes 19 which suspend the lubricant holding cup 20 extends through grooves 21 formed in the base 22 of the cup 55 and have their arms 23 passed through the eyes 16 and held in place by the securing

nuts 24 positioned above the eyes. Springs 25 are placed upon the arms of these yokes and will serve to yieldably hold the yokes in the proper position for holding the lubricant 60 cup in operative relation to the axle 10. This lubricant cup is provided with end walls 26 and 27 and side walls 28 which extend as shown in the several views so that the cup will inclose the lower portion of 65 the axle. The lubricant is placed in the cup and will be absorbed by the wicks 30 and 31 which wicks are secured to the side walls 28 and the end wall 27 by means of rivets or other fasteners indicated by the numeral 70 32. It should be noted that the end wall 27 is provided with a cutout forming a passageway 33 so that the wick 30 may pass over the upper edge of this wall as shown in Fig. 3 without extending above the upper edges 75 of the side portions of the wall. These wicks may be formed of any suitable material such for instance as sheet wool on the hide, felt or any other suitable material which will absorb the liquid lubricant and at the same 80 time wear well.

When in use, the journal lubricator is assembled as shown in the drawing and as the train moves along the track, the axles will rotate and will receive oil from the wick 31. 85 The wick 30 which extends over the edge of the wall 27 will not only serve to apply oil to the axles but will also serve to apply oil to the hubs of the wheels. Therefore, the axles and the wheels will be well lubricated 90 and will thus run easily. If the oil needs replenishing or if it is necessary to clean the lubricant receptacles and refill them, the nuts 24 are removed so that the lubricant 95 receptacles can then be dropped and either entirely removed for cleaning or if it is only desired to refill them, that they may be re-filled and then put back into place. When the wicks are worn out, they can be easily removed and new wicks put in place. It 100 will thus be seen that this journal lubricator will continuously lubricate the axles and wheels thus causing the wheels and axles to rotate easily.

What is claimed is:—

1. A journal lubricator including a frame, an upper bearing block in said frame, an axle extending through the frame and engaged by the upper bearing block, a bearing cup positioned beneath the axle, said bearing cup constituting a lubricant receptacle having side walls and end walls, one of the end

105

110

- walls being provided with a cutout leading from its upper edge, applying wicks secured to the side walls and one of the end walls of said lubricant cup, the wick of the end wall 5 extending through the cutout thereof and down the outer face of the end wall for applying lubricant to the hub of a wheel carried by said axle, and means for supporting the lower bearing cup beneath the axle and 10 in operative relation thereto.
2. A journal lubricator including a frame, an upper bearing block positioned in said frame, an axle extending through the frame beneath the upper bearing block and in engagement therewith, a lubricant receptacle positioned beneath the axle, and including side walls and end walls, one of the end walls being provided with a cutout leading from its upper edge, applying wicks positioned 15 within the lubricant receptacle for engaging the axle, one of the wicks extending through the cutout of the end wall and along the outer face of the end wall, and means for holding said receptacle in position 20 beneath the axle.
3. A journal lubricator comprising a frame, an upper bearing block in said frame, an axle extending through the frame beneath the bearing block, a lubricant receptacle positioned beneath the axle, applying wicks in 25 said receptacle, one of the wicks extending out of the receptacle for engaging the hub of a wheel carried by said axle, and means for holding said receptacle in place beneath the axle.
4. A journal lubricator comprising a frame, an upper bearing block in said frame, an axle extending beneath said block, a lubricant receptacle beneath said axle including 30 side walls and end walls, applying wicks positioned within the receptacle against the side walls and one of the end walls, the wick 35

of the end wall extending over the same and down against the outer face of the end walls, and means for holding said lubricant 45 receptacle in place beneath the axle.

5. A journal comprising a frame, an axle extending through said frame, a lubricant receptacle extending beneath said axle, lubricant applying means carried by said receptacle and extending out of the same for engaging the hub of a wheel carried by said axle, and means for holding the receptacle in operative relation to said axle.

6. A lubricant receptacle for a car journal 55 having a bottom, side walls extending divergently from the bottom, end walls provided with curved upper edges, one of the end walls being provided with a notch leading from its upper edge to provide a passageway, applying wicks fitting against the side walls, and an applying wick fitting against one end wall and passing through the notch in the end wall.

7. A lubricant tray for a car journal comprising a bottom, side walls extending from 60 said bottom, end walls having curved upper edges adapted to contact with an axle, and applying wicks fitting against the side walls and against one of the end walls and extending 65 over the edge of the same to extend along the outer face of the end wall.

8. A lubricant pan for a car journal having side walls and end walls, and applying wicks connected with the side walls and one 70 of the end walls, the wick of the end wall extending over the same for applying lubricant to a wheel fitting upon the axle.

In testimony whereof I affix my signature in presence of two witnesses.

EDWARD H. ERNST.
